VERTICAL SOLID FUEL BARBECUE GRILL

James R. Headberg, 10250 SW. 156th St.,
Miami, Fla. 33157

Filed May 7, 1973, Ser. No. 357,687

Term of patent 14 years

Int. Cl. D7—04

U.S. Cl. D7—110

FIG. 1 is a side elevation of vertical solid fuel barbecue grill, showing my new design.

FIG. 2 is a top plan view thereof.

FIG. 3 is a side elevation of the grill, taken at right angles to that shown in FIG. 1.

FIG. 4 is a bottom plan view thereof.

I claim:

The ornamental design for a vertical solid fuel barbecue grill, as shown and described.
